UNITED STATES PATENT OFFICE.

ARTHUR GIESLER, OF DAYTON, OHIO, ASSIGNOR TO THE STILWELL-BIERCE
& SMITH-VAILE COMPANY, OF SAME PLACE.

GAS-COMPRESSOR.

SPECIFICATION forming part of Letters Patent No. 556,713, dated March 17, 1896.

Application filed October 3, 1895. Serial No. 564,501. (No model.)

To all whom it may concern:

Be it known that I, ARTHUR GIESLER, of Dayton, county of Montgomery, State of Ohio, have invented a new and useful Improvement 5 in Gas-Compressors; and I do declare the following to be a full, clear, and exact description of the invention, such as will enable others skilled in the art to which it appertains to make and use the same, reference being had 10 to the accompanying drawings, and to the letters of reference marked thereon, which form a part of this specification.

This invention relates to new and useful improvements in gas compressors or pumps 15 for use in connection with machinery for producing cold, and known in the art as "refrigerating" or "ice-making" machines of the character that employ gas that is subject to liquefaction under mechanical compression— 20 for example, anhydrous ammoniacal gas—the subsequent expansion of which produces the refrigerating agent.

Heretofore it has been difficult to construct a gas-compressor with a capacity for making 25 small quantities of ice without correspondingly decreasing the efficiency of the compressor, and so far as I am aware this inefficiency and difficulty have been largely due to the general construction of the compressor 30 and the multiplicity of parts and their connections.

One of the objects, therefore, of this invention is to overcome the above objections and defects by providing an efficient gas-compressor and one that has a capacity for pumping 35 dry gas.

A further object of said invention is to provide a compressor the moving parts of which are comparatively few in number and practically free from undue friction, in order that 40 the same may require little or no attention during the operation of the machine.

In the attainment of these objects the said improvements have reference to means for 45 sealing the oil and gas chambers without the use of a stuffing-box. The said improvements have a further reference to the employment of the fewest possible number of moving

parts between the crank-shaft and the piston and to the construction of said piston. 50

Referring to the annexed drawings, which form a part of this application, Figure 1 is a sectional elevation of my improved duplex gas-compressor. Fig. 2 is a sectional elevation at a right angle to Fig. 1. 55

In the specification similar letters of reference will denote corresponding parts in the different views.

As one piston-cylinder, piston, and adjunctive devices are counterparts of the other, the 60 specification will be confined to a description of one side of the pump.

A designates the housing, which is inclosed at the top by a water-jacket A', having inlet and outlet ducts q and q'. The lower portion 65 of said housing has a crank-chamber B that is inclosed by bonnets A'' and is adapted to contain a quantity of oil B', to the height substantially as shown, and in which the crank-shaft is submerged. C designates said crank- 70 shaft, which is journaled in bearings on said bonnets, and D is the piston-cylinder, which occupies a position to one side of the crank-shaft, as shown in Fig. 2. This cylinder has an annular flange D', which rests upon and 75 is made secure to the upper end of the housing, and a lower flange b that abuts with an annular projection on the interior of the housing. The lower end of said cylinder extends 80 downwardly in proximity to the oil and is provided with ports t t, through which the oil that is splashed upwardly from the oil-chamber may pass to the upper part of the connecting-rod. When the said cylinder is placed in position there is formed a gas-chamber f that is 85 outwardly-inclosed by a cover b', the inner edges of which are sealed to the exterior of said cylinder. Gas is inducted from the chamber f to the cylinder-chamber h through ports e e and out through a discharge-valve a to the 90 discharge-pipe F'.

F designates an induction or suction pipe, which is tapped into the cover b' and forms a communication between the chamber f and the freezing-tank. (Not shown.) 95

E designates the cylinder-head, which is

mounted on the cylinder. This head incloses the seat c' for the outlet-valve a , through which the ammoniacal gas is discharged under pressure. a' is an annular gas-chamber or duct extending around the interior of the cylinder-head and communicating with the valve-seat c' , from whence gas passes to the discharge-pipe F' through a channel a'' , as is shown in broken lines in Fig. 2. The extent of the movement of this valve is governed by the space z between the upper end of said valve and the cap b' . The piston I has its middle portion reduced in diameter and provided with oblong ports s , through which gas is inducted to the piston-chamber s' . g is a concaved diaphragm which separates said chamber s' and through the center of which there is a port or opening o , through which gas may pass to the chamber B until the volume and pressure of the gas therein equals that in the cylinder. Incidentally the opening o also affords a passage for any oil that might find its way up the sides of the piston to return to lubricate the wrist-pin and connecting-rod. The said connecting-rod has its upper end projecting into the lower end of the piston and is connected directly thereto by the wrist-pin. The lower end of said connecting-rod is connected to the crank-shaft C , which, as hereinbefore stated, is out of alignment with the vertical center of said piston, so that the lines of force exerted by the connecting-rod will be tangential or on an angle to the center of said piston, and the amount of strain on the piston connections is consequently materially reduced. c'' is a valve-seat in the upper end of the piston, and in which an inlet or suction valve c is placed, the lower end thereof being inclosed by a lock-nut e'' . Upon the downstroke of the piston gas will pass through ports i' , above the valve c , and upon the upstroke said gas is forced through the discharge-valve a . A uniform pressure above and below the valve c is created upon the downward movement of the piston. Therefore the said valve is enabled to seat itself by gravity. g' designates two series of sealing-rings surrounding the piston. The upper series of these rings form a seal to prevent the passage of gas from the upper part of the chamber h , while the lower series form a seal between said chamber and the oil-chamber that effectually prevents any communication between said chambers after the oil-chamber has received an amount of gas equal to the pressure in the chamber h . The pipes constituting the freezing system are therefore kept free from accumulations of oil and a more efficient freezing capacity is maintained, and, further, the compressor is enabled to run with gas that is unmixed with oil and is in an absolutely dry state.

To more particularly illustrate, a brief description is given. Assuming that the com-

pressor is about to be started, the gas-chamber f is supplied with gas under suction-pressure from fifteen to thirty pounds, this being the most desirable pressure. The upward movement of the piston will create suction below it, and continuing will compress gas above it and discharge the same through the valve a to the pipe F' . The oil-chamber at the start being free from gas, the continuous movement of the piston will cause a certain quantity of gas to pass the lower sealing-rings g' and through the port o until the volume or specific gravity of the gas thus entering the oil-chamber equals that in the cylinder or gas-chambers h . When this equilibrium is established, all communication back and forth between said chambers ceases, and the compressor is in a condition to furnish a dry and pure refrigerating agent to the freezing system. A further advantage may be mentioned as attainable by thus supplying the oil-chamber with gas to equal the suction-pressure, namely: The crank-shaft bearing will be relieved by said pressure on the upward stroke of the piston in exact proportion to the amount of pressure exerted on said piston by the gas in the chamber h . This upward pressure on the piston, it will be observed, is obtained at a time when most needed—to wit, when the strain is put upon the crank-shaft. Consequently the strain thus put upon the piston-bearings and the crank-shaft will be greatly relieved.

Having fully described my invention, I claim—

1. In a gas - compressor, the combination with the housing providing an oil-chamber B and the piston-cylinder, of a single-acting piston provided with a chamber separated from the oil-chamber by a concaved perforated diaphragm, a suction-valve in the upper end of said piston, a connecting-rod projecting into the lower end of said piston and connected thereto and to the crank-shaft, a series of sealing-rings on said piston whereby means are provided for establishing an equilibrium between the oil and gas chambers which enables the pumping of dry gas.

2. In a gas - compressor, the combination with a piston-cylinder, an exterior gas-chamber, and ports e communicating therewith from the cylinder-chamber, and a discharge-valve mounted on the upper end of said cylinder, of a piston having its upper portion hollow, and oblong ports communicating therewith, a suction-valve seated in the upper end of said piston, a connecting-rod projecting into the lower end of said piston, and sealing-rings carried on the piston below the oblong ports, whereby means are provided for sealing the oil and gas chambers from each other without the aid of a stuffing-box, substantially as described.

3. In a gas - compressor, the combination with a cylinder, and an exterior gas-chamber

having ports communicating with said cylinder, of a piston having its central portion of a smaller diameter and provided with a gas-chamber with ports communicating with the cylinder, a concaved diaphragm forming the bottom of said chamber and provided with a port in its center, an oil-chamber below the piston, an upwardly-opening suction-valve seated in the upper end of said piston, and a

discharge-valve seated vertically above said suction-valve, substantially as and for the purposes specified.

In testimony whereof I have hereunto set my hand this 24th day of September, 1895.

ARTHUR GIESLER.
